UNITED STATES PATENT OFFICE.

THOMAS THEODORE BERNARD, OF ST. LOUIS, MISSOURI.

RACK.

Application filed June 29, 1925. Serial No. 40,433.

This invention relates to racks, and more particularly to a store fixture adapted to hold and display to advantage greeting and private post cards and the like. The conventional manner of presenting such commodities to the public is to place them in bins, or to scatter them indiscriminately on tables or counters, rendering it difficult and tedious to make selections without excessive handling, and resulting in delays in making sales and in soiling of the cards by careless customers. To spread the articles on tables or counters in order to facilitate their selection requires the allotment of considerable floor space for this purpose. Floor space is a desideratum, because the less the space required for a given volume of business, the more productive is the investment of the store owner. The time necessary to complete a transaction is also of the greatest importance, because the greater the number of sales in a given time, the less is the overhead expense per sale.

Accordingly, one of the objects of this invention is to provide a rack for the purpose set forth which will need less floor space for a given number of commodities than the tables and counters hitherto employed for this purpose.

Another object is to provide a rack which is adapted to expedite the transaction of business; and to this end provides means for displaying the cards in an orderly fashion, and so as to be viewed with a minimum of effort on the part of the observer, and means for most effectively illuminating the same.

Another object is to provide means for displaying only one card of every kind as a sample, the remaining cards of a group to which the sample belongs being arranged in a compact manner in juxtaposition to the sample, thereby rendering unnecessary any handling of the cards for inspection, and preserving them from dust and the finger marks of slovenly patrons.

Another object is to provide a rack having shelves which may be adjusted to accommodate different sizes of cards.

A further object is to provide a novel form of clip which may be readily attached to the shelves for the purpose of holding and identifying the various sample cards or indicating the price thereof or imparting other information that may be desired. Because of the structure and mode of use of this clip, it is extremely adjustable.

It is further contemplated to provide a rack which may be used either as a wall rack, or be combined with another similar rack, thus forming a two-faced or double rack, which may be placed in a more central portion of the store.

A further purpose of this invention is to provide a rack having novel component parts which may be manufactured cheaply in quantity production; and which facilitate the rapid and economical assembly of the same into a complete unit.

Other objects and advantages will appear in the course of the following description of the preferred embodiment of this invention.

In the accompanying drawings forming part of this specification, in which like numbers of reference denote like parts wherever they occur,

Figure 1 is a front elevation of the rack;

Figure 2 is a vertical transverse sectional view of the rack, taken on the line 2-2 in Figure 1;

Figure 3 is an end elevation exhibiting two racks placed with their backs together to form a single unit having two fronts;

Figures 4 and 5 are plan and elevational views, respectively, of the tie employed to connect the racks together;

Figure 6 is a fragmentary enlargement elevation, partly in section on the line 6-6 in Figure 8;

Figure 7 is a plan view of a transverse partition;

Figure 8 is a fragmentary vertical transverse sectional view taken on the line 8-8 in Figure 1;

Figure 9 is a similar view showing the shelves holding cards; and

Figure 10 is a perspective view of the sample clip adapted for attachment to the shelves of the rack as it appears when detached.

The framework of the rack is preferably constructed of wood and comprises upright boards 1 arranged transversely at each end and connected at the top by horizontal board 2 and at a moderate distance from the floor by a horizontal board 3, which may also serve as the lowest shelf. Feet 4 are preferably secured to the lower ends of the upright members 1. A vertical panel 5 connects the members 1 between the shelf 3 and the feet 4. Panel 5 braces the frame longitudinally, and members 2 and 3 brace

it transversely. Brackets 6 are secured to the upper end portions of the uprights 1, and together with top board 3, project beyond the front face of the rack to form a canopy 7. A board 8 connects the outer ends of the brackets 6 and forms a depending flange for the board 3. A fibre-board backing 9 is secured to the rear ends of the members 1, 2, and 3. The several parts 5 may be connected together in any conventional manner, preferably by means of suitable nails.

Shelf-supporting strips 10 are secured to the inner sides of upright pieces 1 adjacent 15 to the longitudinal edges thereof and between the bracket 6 and the fixed shelf 3. The strips 10 are preferably formed of sheet metal and have a series of inwardly-extending 20 projections 11 alternating with another series of inwardly-extending projections 12. The projections 11 and 12 are preferably in the form of flanges struck out from the body of the strip by partly severing portions of the strip as at 13 and 14, respectively, and bending them inwardly at a right angle preferably, the flanges 11 being perpendicular to the longitudinal edges of the strips, and the flanges 12 being inclined 25 upwardly toward the forward edges of the strips, forming a tapered channel 15 to receive the shelves 16, the rear ends of the channels snugly fitting the shelves and the forward ends being wider to form a mouth 30 to facilitate the insertion of the shelves 35 thereinto. The strips 10 are perforated for the passage of nails 17, by means of which they are secured to the upright members 1.

The shelves 16 have secured to their front 40 ends the upwardly extending flanges 18, provided with openings 19, affording a view of those portions of the contents that would otherwise be concealed by the flanges 18 in the absence of the openings 19. The flanges 18 are preferably formed of upper and 45 lower strips of wood 20 and 21, respectively, connected by interviewing blocks 22, the various parts being preferably nailed together, and the flanges nailed as units to the front ends of their respective shelves. 50 The flanges 18 on the upper shelves are preferably vertical in the direction of their width; the flange on the lowest removable shelf 16 preferably reclines slightly from the vertical position toward the rear; and 55 the flange 18 on the fixed shelf 3 preferably reclines still further in the same direction. The reclination of the lower flanges enables any display matter on their outer faces to be viewed with a minimum of effort on the 60 part of an observer, because these flanges are lower than the eyes of the observer, and their being inclined at respective acute angles to the shelves places their outer faces more nearly at a normal to the line of sight 65 of the observer. Partitions 23 may be

placed on the shelves 16 at suitable intervals to separate one group of commodities from another. The partitions 23 are preferably formed of sheet metal, and have respective portions of their lower ends bent 70 at right angles in opposite directions to form supporting feet 24 to maintain the partitions in an upright position.

A sample 25 of the individual cards 26 or the like constituting a group may be displayed on the outer side of the flange 18 of the shelf, being secured thereto directly in front of its related group 26 by means of substantially L-shaped clips 27, adapted to clamp the lateral edges of the sample 25 80 against the flange 18, so as not to obscure the matter displayed thereon. Each of the clips 27 is preferably formed of a resilient strip of sheet metal bent into shape and having prongs 28 struck from one of its arms 29 and bent inwardly at right angles thereto. The other arm 30 has its upper portion 31 bent slightly inward, so that, when the clip is attached to the shelf by pressing the prongs 28 against the under side of the shelf with the lower portion of the arm 30 against the flange 18, the upper portion 31 will tend to press that portion of the card on which it bears into the opening 19, giving the card a slightly arcuate shape and thus holding it more securely against the strips 20 and 21. The clips 27 may bear on their outer faces various markings or designating characters 32, such as the price of the card held by the clips. The shelves having the reclining flanges may have their forward edges beveled to fit the same, and the forward portion of their bottom surfaces beveled at right angles to their forward beveled edges to accommodate the pronged arm of the 105 clips.

The canopy 7 contains therein a reflector 33, adapted to reflect the light from electric lamps 34 against the front face of the rack so as to illuminate all the matter displayed thereon, and yet shield the eyes of the observer from direct light from the lamps. The reflector 33 is preferably formed of bright sheet metal, secured to the canopy in any suitable manner, being of arcuate section and extending from one end of the rack to the other. The lamps 34 are secured in the conventional sockets 35, connected to a conduit 36 by nipples 37, passing through the top wall 2. Conduit 36 terminates in a socket 38 situated on the top of the rack and adapted for connection to a plug of a flexible extension from an electric lighting circuit.

A single rack may be placed with its back against a wall to serve as a wall rack, or two racks may be placed with their back sides together and function as a two-faced center rack, as shown in Figure 3. For the purpose of connecting two racks together in this manner, I provide each of the feet 4 125

with pins 39, preferably metal, secured in their upper ends to project upwardly therefrom. Similar pins 39 are similarly secured in the top boards 2 at each outer end thereof. 5 Ties or connector bars 40, preferably wood, have holes 41 in each end which form respective sockets for the corresponding pins 39 of the opposing racks.

Having thus fully described this invention, I hereby reserve the benefit of all changes in form, arrangement, order, or use of parts, as it is evident that many minor changes may be made therein without departing from the spirit of this invention or 15 the scope of the following claims.

I claim:

1. A rack of the character described comprising a series of shelves disposed at different heights and provided with respective 20 flanges on their forward edges, some of the flanges being vertical transversely and others being inclined from a vertical position so as to present their respective outer faces approximately at a normal to the line of 25 sight of an observer.

2. A rack of the character described comprising a series of shelves disposed at different heights and provided on their top sides with respective flanges presenting outer 30 play faces, the upper flanges being substantially vertical, and the lower flanges reclining rearwardly, the reclination of successive shelves increasing in their descending order.

3. A rack of the character described comprising a series of shelves disposed at different heights and provided with respective 35

flanges on their forward edges and having openings therethrough, some of the flanges being vertical transversely and others being inclined from a vertical position so as to 40 present their respective outer faces approximately at a normal to the line of sight of an observer.

4. A rack of the character described comprising a pair of oppositely disposed end 45 walls, a pair of shelf-supporting strips secured on the inner side of each end wall adjacent the longitudinal edges thereof, the said strips bearing alternative shelf-supporting projections, one series of alternative projections being angularly disposed and a plurality of shelves borne at their respective 50 corners by corresponding projections, said angularly disposed projections clamping the upper faces of said shelves.

5. A rack of the character described comprising a pair of oppositely disposed end walls, a pair of shelf-supporting strips secured on the inner side of each end wall adjacent the longitudinal edges thereof, the 60 said strips bearing alternative shelf-supporting projections, one series of alternate projections being angularly disposed to present a tapered channel therebetween and a plurality of shelves borne at their respective 65 corners by said projections and fitting into the tapered channels formed by said projections.

In testimony whereof I hereunto affix my signature.

THOMAS THEODORE BERNARD.
